APPARATUS FOR TRANSMITTING
RECORDING GRAPHICS

Georges Delchef, Brussels, Belgium

Application June 22, 1935, Serial No. 27,898
In Belgium June 22, 1934

8 Claims. (Cl. 178—69.5)

My present invention relates to an apparatus for transmitting recording graphics, of the kind in which electric contact pieces synchronically travel in relation to two surfaces, the one transmitting and the other receiving the graphics or messages.

It more especially concerns an apparatus in which a contact member displaces itself according to the generatrix of a drum or practically so, the startings of this contact member being made synchronous on the transmitting device on the one hand and on the receiving device on the other hand.

In such an apparatus, the transmission of messages is only possible in one direction of movement; the return of the contact member taking place (rapidly) in a length of time always under a given time, so that the contact members may be able to resume their former position previous to going over another line, the drum (of transmission on the one hand and of reception on the other hand) being subjected meantime to a slight rotation.

This method allows of a transmission notwithstanding a difference of speed between the driving members of the transmitting device and of the receiving device and permits the use of a receiving band which is not limited in dimensions to the surface of the carrying drum.

My present invention has for its object to provide an apparatus reliable in its working, involving the use of no complicated parts namely for the synchronization, and in which the passing from the transmitting position to the receiving position is particularly simple.

With this object in view, my invention essentially consists in the special arrangements of parts hereinafter fully described and pointed out in the appended claims.

The attached drawings show one form of the apparatus by way of example.

Figure 1 is a plan view showing the arrangement of the apparatus.

Figures 2 and 3 are detailed views showing the arrangement of the transmission and receiving surfaces.

Figures 4 to 7 are views in detail.

Figure 8 shows a diagram of the circuit arrangements.

Figures 9 and 10 show modifications of the embodiment.

In the example shown, the apparatus represented in Figure 1 consists of a base 1 carrying at one end a rectangular container formed by plates 2, 3, 4 and 5. The base 1 carries a motor 7 pro-

vided with a centrifugal brake 8 on the fly-wheel of which is mounted a device 10 which if desired can be employed to convert the transmitting current from continuous to alternating.

The motor drives a shaft 9 which carries a worm 11 engaging with a worm wheel 12 mounted on a shaft 13. The latter carries at one end a coupling electromagnet 14 and at the other end a toothed pinion 15 which engages with a toothed wheel 16, which carries a cam 17 and a pin 18. This pin 18 co-operates with a lever 20 which oscillates about an axis 21 (Figure 5) and has a projection for operating the contacts 103—104.

The cam 17 actuates a lever 19 (Figure 6) furnished with a pawl 23 arranged to act on a ratchet wheel 24. This ratchet wheel has a smooth part furnished with a notch 25 and carries a pin 26 arranged to operate a lever 27 incorporating a plate 28 to which it is electrically connected. This lever 27 has an extension at the end in contact with the pin 26 consisting of a blade 27¹ provided with a projection 27² by means of which it can act on a lever 78 the function of which will be explained later. At the opposite end the lever 27 has an extension 28 provided with contact members 107 adapted to engage either with contacts 108' or contacts 108'' according to the position of the lever. The notch 25 serves to receive a pin 29 forming part of the armature 30 of an electromagnet 31. As shown in Fig. 6 when the armature 30 is in the energized position contacts 101 and 102 are closed.

Facing the electromagnet 14 is a pulley 32 (Figure 1) which is mounted on a shaft 33 carrying a helix 34 arranged to move the rods 35 and 36 by means of the pins or blocks 35' and 36'.

The rod 35 has only for its function to guide the whole constituted by the rod 35, the helix 34 and the blocks 35', 36'.

The shaft 33 carries at its end a spring 37 which presses on the one hand on a ball-bearing abutment 38 and on the other hand on a plate 39. The end of the shaft 33 rests in contact with the end of a screw 40. Under the electromagnet 14 and the pulley 32 is a block 41 mounted on guide rods 44 and 45 and which can be displaced by the manual operation of a push button 42 which is situated at the end of a rod 43 fixed to the block. The block 41 can be operated only manually against the action of springs 41' and is held in the operated position by the lever 78 which enters a notch in the rod 43. When this lever is tilted under the action of the lever 28 (Fig. 6) the block 41 is freed and returned to its normal position by the springs 41'. The block 41 carries a

plate 46 pivoted as shown in Figure 4 and carrying a lever having a vertical arm 47 and a horizontal arm 48 (Figure 1). The lever 47-48 is adapted to be tilted under control of the rod 36 so that it acts either on a lever 49 or on a lever 50, which are both mounted freely on a shaft 51. The lever 50 acts by means of a pawl 52 on a ratchet wheel 53 which is fixed on the shaft 51 carrying the receiving cylinder 58. The lever 49 acts by means of a pawl 56 on a ratchet wheel 57 rigidly connected to the transmitting cylinder 55. Thus either the receiving cylinder or the transmitting cylinder is operated according to the position of the block 41.

15 The assembly of the receiving and transmitting cylinders comprises (Figures 2 and 3) a fixed cylindrical portion 59 partly surrounding the receiving cylinder 58. The latter (if an electrolyte is used) consists of a cylinder about which is wrapped the sensitized receiving band of paper. A sleeve 60 serves to support the cylinder 58 and can permit of it being filled with the solution destined for the electrolysis.

20 The transmitting cylinder 55 comprises a section of a hollow cylinder having annular ends. A contact member, for example a small style 61, is carried by a movable support 62 to which is fixed a cord fixed on the one hand to the pulley 32 and on the other hand to the return pulley 61'. The 25 slide 62 moves along the transmission or reception cylinder being guided by wires 63 fixed on the one hand to screws 64 penetrating the plates and on the other hand to screws 65 fixed in a support 66 mounted on the base 1, which also supports the cylinders. When the carriage 62 reaches the end of its traverse i. e. at the left hand position in Fig. 1, a contact 100 is opened. This contact is not shown in Fig. 1 since its function is purely electrical but it is indicated in the circuit diagram of Fig. 8.

40 The movable block 41 (Figure 4) has an arm 67 extending from its underside which carries a roller 68 arranged to operate on a control switch 69 having several contact springs which are fixed at one 45 end to a contact support 70.

45 The contact springs 69 carry the contacts 1, 2, 3, 4, 5 (Figure 8) and due to their elasticity make contact with the contacts R1, R3, R5 when the roller 68 is moved to the right (condition for reception). This roller when displaced to the left 50 presses on the contact springs which therefore make contact with the terminal contacts E2, E3, E4, E5 (condition for transmission).

55 The condition of contacts 3 serves to control certain circuits to be indicated later and which determine whether the apparatus is to be used for transmission or reception. In fact with the contacts in the condition shown in Fig. 4, i. e., with the knob 42 pressed in the apparatus is set for 60 transmission. The release of the knob under the control of the lever 28 as described above conditions the apparatus for reception.

65 The rod 36 (Figure 1) acts at one end on a spring 78 (Figure 7) which is fixed to a support 79', located at the rear of the apparatus and which carries two contacts 105 and 106 on opposite sides which co-operate with fixed contacts 105' and 106'.

70 This spring is so arranged that when the contacts 105-105' are in the open position, the contacts 106-106' are in the closed position and vice versa.

75 In the position shown in the drawings the pin 78 acts on the lever 27 whereby contacts 107 are connected to contacts 108' so that the electromag-

net 31 is connected to the line over conductors 80. If the apparatus is required to transmit signals two manual operations must be performed. First the knob 42 is pressed inwards to cause contacts 2, 3, 4 and 5 to engage with contacts E2, E3, E4 and E5 and second the armature 30 is lifted so that the pin 29 is removed from the slot 30 (Fig. 6). As a result of the second operation contact 102 is closed and the motor M is energized over the circuit: +HT, conductor 84, 84', winding 10 M of the motor, conductor 84, contact 102, -HT. A circuit is also closed for electromagnet 14 over: +HT, electromagnet 14, normally closed contact 100, resistance R5000, contact 102, -HT. Due to resistance R5000 the current in the circuit is insufficient to cause the energization of the electromagnet. The motor, however, commences to rotate whereupon the pin 26 is moved away from the lever 27 and the electromagnet 31 is disconnected from the line L-L₁ and connected to the 20 anode circuit of the valve T1. Further the pin 18 on the wheel 16 is gradually moved into contact with the arm 20 to cause the closing of contacts 103 and 104. Calling signals are now transmitted over the line due to the closing of the circuit: s', contact 103, conductor 82, contacts 2, E2, conductor 82, 10, conductors 82 primary winding of transformer T_r, s. A source of low frequency alternating current is connected to s-s' and serves as a calling signal. The closure of contact 104 short-circuits resistance R5000 over contacts E4, 4, conductor 88 and contact 104. Current is now sufficient in the above-traced circuit for electromagnet 14 to allow the latter to operate. As a result armature 32 is attracted and the carriage 62 is set in motion.

25 At the other end of the line the calling signal passes over conductor 80, contacts 108' and 107 to the winding of the electromagnet 31.

30 The electromagnet 31 is thus energized through its first step to close contact 102 only so that the armature 30 takes up the position shown at b in Figure 6. Contact 102 thereupon closes a heating circuit for the valves T1 and T2 as follows: +HT, conductor 84, resistance R600, filaments of valves T2 and T1 in series, conductor 86, contacts R1, 1, 102, -HT. Further as pointed out above when the motor commences to rotate due to the closure of contacts 102 the electromagnet 31 is disconnected from the line L-L₁ and is connected in parallel with the anode circuit of the valve T1. As in the case of the transmitting apparatus the closure of contact 102 also completes a circuit for electromagnet 14 but this does not operate due to the resistance R5000 which is included in the 35 energizing circuit. However, as soon as anode current commences to flow electromagnet 31 is energized through its second step and takes up the position shown at c in Figure 6 whereupon contact 101 is closed. Resistance R5000 is thereby 40 short-circuited and the electromagnet 14 now operates over its energizing circuit and the carriage 62 at the receiving station commences to advance.

45 The anode potential of the valve T2 is obtained by a direct connection thereto from conductor 87 while the anode circuit of valve T1 extends over: conductors 93 and 94, contacts R5, 5, receiving cylinder C, receiving paper, stylus 61, conductor 92, contact 106, 3, R3, conductors 95, 84, +HT, 50 contact 106 being closed on the commencement of rotation of the motor by the axial movement of the rod 36.

55 At the transmitting station contact 106 is also closed on the movement of the motor and a 55

circuit is then closed extending as follows: terminal s , transformer T_r , conductor 82 , contacts $E3$, 3 , contact 106 , conductor 92 , stylus 61 , transmitting paper, cylinder C , contacts 5 , $E5$, conductor 91 , $91'$, terminal s' . Picture currents, therefore, flow over the transformer T_r and pass over the line $L-L_1$ to the receiving station where they are applied to the grid of the valve T_2 over the circuit: filament of valve T_2 , conductors 83 , 82 , winding of transformer T_r , conductor 83 to the grid. The anode current of the valve T_1 thus fluctuates in accordance with the incoming signals and since the anode circuit includes the stylus 61 , a trace is made on the receiving paper corresponding to that at the transmitter.

When the carriages 62 at the transmitting and receiving stations reach the end of their traverse, the respective rods 36 engage with the lever $47-48$ to cause the stepping of the receiving and transmitting cylinders as described above. Further contacts 100 are opened to cause the de-energization of electromagnets 14 whereby the motor is decoupled from the driving mechanism and the carriages 62 move back to their starting positions under spring tension. Contacts 100 are again closed and the electromagnets 14 are again energized and the cycle of operations commences. It will be understood that the armature 30 of the electromagnet 31 is maintained in position at the transmitter due to the fact that the pin 29 is riding on the periphery of the wheel 24 , the latter making one revolution while a complete picture is transmitted, while at the receiver the electromagnet 31 is maintained energized in its second step by the anode current from valve T_1 . At the termination of transmission and reception contacts 107 and 108 are separated and the pin 29 comes into alignment with the slot in the wheel 24 so that electromagnet 31 is returned to normal at both stations, the motors stop and the transmitting station is returned to its normal condition of reception.

In the case where the line $L-L_1$ is a telephone line it may be necessary to provide a direct current loop in order to hold certain exchange apparatus in an operated condition. Such a holding circuit is closed on the operation of contacts 108 (Fig. 6) as follows: L , choke Sc , conductor 81 , contact 108 , conductor 81 , L' .

In connection with the operation of electromagnet 14 it should be noted that if a source of direct current of 110 volts is employed and an air gap of 0.6 mm. is provided for the electromagnet 14 the resistance of the winding being 1000 ohms (by using a wire of 0.1 mm. diameter) and that of resistance R_{5000} being 5000 ohms, it will follow that the holding current, which is insufficient to actuate the wheel 32 but sufficient for ensuring its holding maintenance when once operated, will be approximately 20 milliamperes. The short circuiting of the resistance would decrease the current to approximately 110 milliamperes which is sufficient instantaneously to overcome the air gap mentioned above and cause the actuating of the wheel.

It will be noticed that by manipulating a knob $24'$ co-operating with wheel 24 it is possible to reduce or to prolong the time of operation of the apparatus as indeed this wheel 24 controls the different circuits.

I claim:

1. In an apparatus of the type described, the combination comprising a transmitting-recording member and a cooperating contact element adapted to be relatively displaced, and driving

means therefor including an electromagnetic clutch comprising an electromagnet and an armature, means for energizing the electromagnet to effect the attraction of the armature, means for reducing the energization of the electromagnet to effect a retention of the attracted armature but insufficient to attract the armature when displaced, and means for effecting the actuation of said last mentioned means.

2. In an apparatus of the type described, the combination comprising a transmitting-recording member and a cooperating contact element adapted to be relatively displaced, and driving means therefor including an electromagnetic clutch comprising an electromagnet and an armature, means for energizing the electromagnet to effect the attraction of the armature, means for reducing the energization of the electromagnet to effect a retention of the attracted armature but insufficient to attract the armature when displaced, and means actuated by the contact element for effecting the actuation of said last mentioned means.

3. In an apparatus of the type described, the combination comprising a cylindrical transmitting-recording member and a cooperating contact element movable axially of the cylinder and driving means therefor comprising an electromagnetic clutch including an electromagnet, an armature, means for energizing the electromagnet to attract and hold the armature, means for reducing the energization of the electromagnet to effect a retention of the attracted armature but insufficient to couple the elements of the clutch or attract the armature when displaced, and means for effecting the actuation of the last mentioned means.

4. In an apparatus of the type described, the combination comprising a transmitting-recording member, a co-operating stylus adapted to be displaced relative to the transmitting-recording member, a motor for driving the same, an electromagnetic clutch for connecting the stylus for actuation by the motor including an electromagnet and an armature, a clutching circuit for the electromagnet including a branch circuit having a resistance therein, the resistance being such as to permit a current flow sufficient to energize the clutch to retain the attracted armature but insufficient to attract the armature when displaced, means for energizing the clutch through the resistance, means for short-circuiting the resistance to effect full energization of the clutch to attract the armature and cause the stylus to be displaced, and means for effecting the deenergization of the clutch.

5. In an apparatus of the type described, the combination comprising a transmitting-recording member, a co-operating stylus adapted to be displaced relative to the transmitting-recording member, a motor for driving the same, an electromagnetic clutch for connecting the stylus for actuation by the motor including an electromagnet and an armature, a clutching circuit for the electromagnet including a branch circuit having a resistance therein, the resistance being such as to permit a current flow sufficient to energize the clutch to retain the attracted armature but insufficient to attract the armature when displaced, means for effecting energization of the clutch through the resistance, a switch for short-circuiting the resistance, another switch for effecting electrical impulses in the circuit and means for simultaneously closing the switches.

6. In an apparatus of the type described, the

- combination comprising a transmitting-recording member, a cooperating stylus adapted to be displaced relative to the transmitting-recording member, a motor for driving the same, an electro-
5 magnetic clutch for connecting the stylus for actuation by the motor including an electromagnet and an armature, a clutching circuit for the electromagnet including a branch circuit having a resistance therein, the resistance being such as
10 to permit a current flow sufficient to energize the clutch to retain the attracted armature but insufficient to attract the armature when displaced, means for effecting energization of the clutch through the resistance, a switch for short-cir-
15 cuiting the resistance, another switch for effecting electrical impulses in the circuit and means for simultaneously closing the switches including a rotating shaft and a wheel on the shaft.
7. In an apparatus of the type described, the
20 combination comprising a transmitting-recording member, a cooperating stylus adapted to be displaced relative to the transmitting-recording member, a motor for driving the same, an electro-
25 magnetic clutch for connecting the stylus for actuation by the motor including an electromagnet and an armature, a clutching circuit for the electromagnet including a branch circuit having a resistance therein, the resistance being such as to permit a current flow sufficient to energize the clutch to retain the attracted armature but
30

insufficient to attract the armature when dis-
placed, means for effecting energization of the clutch through the resistance, a switch for short-
circuiting the resistance, another switch for ef-
fecting electrical impulses in the circuit and
means for simultaneously closing the switches
and means actuated by the stylus for opening
the clutching circuit to effect deenergization of
the clutch. 5

8. In an apparatus of the type described, the 10
combination comprising a transmitting-recording member, a cooperating stylus adapted to be displaced relative to the transmitting-recording member, a motor for driving the same, an electro-
15 magnetic clutch for connecting the stylus for actuation by the motor including an electromagnet and an armature, a clutching circuit for the electromagnet including a branch circuit having a resistance therein, the resistance being such as
20 to permit a current flow sufficient to energize the clutch to retain the attracted armature but insufficient to attract the armature when displaced, means for effecting energization of the clutch through the resistance, a switch for short-cir-
25 cuiting the resistance, another switch for effecting electrical impulses in the circuit, means for intermittently actuating said switches simulta-
neously, and means actuated by the stylus for effecting deenergization of the clutching circuit. 25

GEORGES DELCHEF. 30
